(73) Assignee: **Suncast Corporation**, Batavia, IL (US)

(57) **CLAIM**

The ornamental design for a ice scraper with brush and hardened tip, as shown and described.

DESCRIPTION

FIG. 1 is a upper perspective view of the ice scraper with brush and hardened tip of the instant invention;

FIG. 2 is a lower perspective view thereof;

FIG. 3 is an enlarged front end view thereof;

FIG. 4 is an enlarged back end view thereof;

FIG. 5 is a right side view thereof, the left side forming a mirror image thereof;

FIG. 6 is top view thereof;

FIG. 7 is a bottom view thereof;

FIG. 8 is an exploded view of FIG. 2 depicting the hardened tip; and,

FIG. 9 is an exploded view of FIG. 1 depicting the hardened tip and brush detached.

1 Claim, 8 Drawing Sheets
